STATOR CONSTRUCTION FOR TURBINE ENGINES

Edward Neshan Movsesian, Stoneham, Mass., assignor to
General Electric Company, a corporation of New York

Filed June 29, 1959, Ser. No. 823,702

7 Claims. (Cl. 253—78)

This invention relates to a stator construction for turbine engines, and more particularly to an improved construction for mounting segmented guide vane assemblies in a stator structure.

Guide vane assemblies commonly used in turbine engines comprise a row of vanes circumferentially spaced about supporting shroud rings, which are secured to radially inner and/or outer ends of the vanes. It has been found desirable to divide such an assembly into a plurality of arcuate segments, so that damaged vanes can be replaced in small groups, without reworking or replacing the entire assembly.

In engines having casings split into semi-cylindrical halves, it is convenient to assemble the vane assembly halves, it is convenient to assemble the vane assembly segments by sliding them circumferentially into grooves formed in semi-circular rabbets in the casing halves. Each segment may be inserted in the grooves at the parting line and slid circumferentially into position. A key may be placed over the grooves and segments at the parting line to restrain relative rotation of the vane assembly after the casing halves are assembled.

However, grooved rabbet structures have not been convenient for use in integral annular casings, because of the difficulty of loading the vane assembly segments in the grooves. Alternative means of fastening the segments in the casing may be used, such as threaded fasteners, but generally the assembly and disassembly procedures are relatively involved and time-consuming, and do not afford as sturdy a construction as the grooved rabbet arrangement.

It is an object of this invention to provide an improved stator construction in which segmented arcuate guide vane assemblies may be easily and rapidly assembled and disassembled in grooved rabbets of an integral annular casing.

It is a further object of this invention to provide a stator construction including improved means for securing an assembly of arcuate guide vane segments in grooved rabbets of an annular casing, facilitating assembly and disassembly of the segments in the casing.

Other objects and advantages of my invention will become apparent from the following description.

Briefly stated, in accordance with one aspect thereof, my invention may be carried out by providing a first annular casing section having an annular recess with spaced parallel grooved rabbets extending circumferentially thereabout, for receiving segmented vane assemblies in circumferentially slidable relationship. A loading slot is formed in the casing in communication with the recess to permit insertion of a vane assembly segment into the recess. The loading slot has sufficient arc length to permit the insertion of one segment at a time. The segment is then slid circumferentially into and along the grooves to its assembled position, and further segments are similarly inserted until a full annular vane assembly is completed.

My invention further comprehends the provision of an arcuate locking strip of congruent form with the loading

slot, which is inserted in the loading slot to retain the vane segments in the casing after assembly. The stator assembly is completed by securing a further casing section to the first casing section. The second casing section **5** overlies the locking strip and prevents its displacement from the loading slot. The circumferential edges of the locking strip and loading slot extend radially, or diverge outwardly of the casing, to secure the locking strip against falling radially into the engine.

10 The locking strip is preferably formed with a groove along an arcuate surface mating with vane segments which are located adjacent to the loading slot upon completion of the assembly, so that these segments are radially supported along both edges in the same manner as the remaining segments.

The locking strip is also preferably formed with a locking lug extending into a mating slot cut in a surface of a vane segment located adjacent to the loading slot, to prevent rotation of the vane segments relative to the **15** casing section by working fluid forces after assembly.

While the specification concludes with claims particularly pointing out and distinctly claiming the subject matter which I regard as my invention, it is believed that the **20** invention may be more clearly understood from the following description of a preferred embodiment, referring to the drawings, in which:

Fig. 1 is an elevation in section of a fragmentary portion of a turbine engine incorporating a preferred embodiment of my improved stator construction, taken on **25** a plane passing through the engine axis;

Fig. 2 is a view taken along line 2—2 in Fig. 1, looking in the direction of the arrows;

Fig. 3 is a view similar to Fig. 1, but taken on a different plane passing through the engine axis;

Fig. 4 is a pictorial view of a vane assembly segment and a locking strip, removed from the engine;

Fig. 5 is an elevation in section of fragmentary portions of the members of Fig. 4, on an enlarged scale; and

Fig. 6 is a view taken along line 6—6 in Fig. 5, looking in the direction of the arrows.

Referring to the drawings, a turbine engine of a conventional type is generally designated at 1. The engine includes one or more circumferentially-spaced rows of rotor blades 2 mounted upon the periphery of a disc 3 for rotation about a common axis. A duct 4 for guiding motive fluid in the direction shown by the arrow through blades 2 is partially defined by an inner shroud ring 5, and by an annular engine casing comprising at least a first section 6 and a second section 7. Radial abutting flanges **45** 8 and 9 are formed about casing sections 6 and 7, respectively, and are joined in fluid-sealing engagement by means of a row of bolts 10 and nuts 11, or by any desired fastening means. Rows of openings 12 and 13 are formed through flanges 8 and 9, respectively, to receive bolts 10.

An arrangement of this general kind may be used for a compressor or a turbine in an engine, blades 2 being appropriately formed for the purpose intended. The engine structure forms no part of the present invention, and **50** will not be further described.

In order to guide fluid flowing through duct 4 in the most advantageous angular path for exit from blades 2, and for entry into subsequent rows or stages of rotor blades, a circumferentially-spaced row of guide vanes 15 is provided, extending across duct 4. Guide vanes 15 are secured near outer ends 16 thereof in mating openings formed in rings 7 and 18 of a composite box-section shroud ring generally designated 19. The vanes are **55** secured in rings 17 and 18 by means of brazing, or in any suitable manner. Shroud ring 19 is divided into a number of segments 20 and 20a (Figs. 2 and 4), to per-

mit replacement of a small group of vanes 15 in the event of wear or damage to individual vanes.

Present practice provides for mounting vane assembly shroud segments in a casing section by means of grooved rabbet structures, in order to afford a sturdy structure which may be easily and quickly assembled and disassembled. However, this arrangement has previously required that the casing section be split into semi-cylindrical halves on a plane passing through the engine axis, to permit insertion of the shroud segments in the grooves of the rabbets. According to my invention, conventional grooved rabbet structures are used in an integral annular casing section 6. For this purpose, circumferential rabbets 22 and 23 are formed on the inner surface of casing section 6 (see Figs. 1 and 3) and are circumferentially grooved at 24 and 25, respectively. A circumferential recess 26 is thus formed in casing section 6 to receive shroud ring 19.

Shroud ring 19 is formed with axially-projecting flanges 27 for circumferential sliding engagement with grooves 24 and 25, by folding the axial edges of ring 17 into radial flanges 28 and U-shaped return portions 29, over the edges of ring 18 (see Figs. 4 and 5). The construction thus far described is conventional, and of itself forms no part of the present invention.

In order to carry out my invention, I form an arcuate loading slot 30 through rabbet 22 (Figs. 1 and 2) extending along an arcuate portion of the rabbet through an arc length at least as great as that of an individual shroud segment 20 or 20a. The shroud segments may be assembled in casing section 6 by inserting them individually through loading slot 30 in an axial direction until a flange 27 engages groove 25 in rabbet 23. Each segment 20 is then slid circumferentially along groove 25, also engaging and sliding in groove 24 of rabbet 22 after leaving the loading slot. The insertion of a last shroud segment 20a in the loading slot completes the assembly of shroud ring 19, and of a complete circumferential row of vanes 15 in recess 26 of casing section 6.

In order to retain shroud ring segments 20 in place in recess 26, and to prevent their rotation relative to the casing after assembly, I provide an arcuate locking strip 32. The locking strip is congruent with loading slot 30, and is identical in cross section with the portion of rabbet 22 milled out to form the loading slot; it includes a groove 33 receiving flange 27 of the last shroud segment 20a. Insertion of the locking strip into loading slot 30 thus effectively completes the annulus of rabbet 22, so that all of the shroud segments are supported along both flanges 27.

Radial movement of locking strip 32 out of loading slot 30 and into duct 4 is prevented by forming circumferentially-spaced edges 34 of the locking strip and mating circumferentially-spaced edges 35 of the loading slot on planes diverging away from the engine axis, as shown in Fig. 2, or on planes radial to the engine axis.

Rotation of vanes 15 and shroud ring 19 relative to casing 6, after assembly, is prevented by means of a stop lug 36 formed on locking strip 32, along groove 33. A notch 37 is cut through an adjacent one of flanges 27 and through ring 18 of segment 20a, to receive stop lug 36. After completion of the assembly of shroud ring 19 in the casing 6, the shroud ring is adjusted by circumferential sliding in grooves 24 and 25, until notch 37 is aligned with lug 36. The locking strip is then insertable into loading slot 30.

The assembly of the vanes 15, shroud ring 19, and locking strip 32 is retained against axial movement relative to the casing by assembling flanges 8 and 9 of casing sections 6 and 7 in abutting relation, and securing the flanges by means of bolts 10 and nuts 11. This completes the assembly of the stator structure.

It will be apparent from the foregoing description that I have provided an improved stator construction by means of which segmented vane assemblies are supported and

secured in grooved rabbets of an integral annular casing section, and which affords facility of assembly and disassembly. No additional fasteners, other than those used to secure the casing sections, are required in the assembly, and this minimizes the labor necessary in assembly and maintenance. With the casing sections parted, the segmented vane assemblies and locking strip may be manually assembled in the casing, or removed for inspection and replacement, without the use of tools of any kind.

It should be understood that my invention is not limited to specific details of construction and arrangement thereof herein illustrated, and that modifications may occur to those skilled in the art without departing from the spirit and scope of my invention.

What I claim as new and desire to secure by Letters Patent of the United States is:

1. In a turbine engine of the type comprising an annular casing partially defining a working fluid duct, a row of blades mounted for rotation in said duct, and a row of 20 guide vanes in said duct for guiding a flow of working fluid therein, a stator construction for mounting said vanes in said casing, comprising, in combination; an annular shroud ring secured to an end of each of said vanes, said shroud ring divided circumferentially into a plurality of 25 arcuate segments, said casing formed with a recess extending circumferentially thereabout for receiving said shroud ring, a pair of spaced-apart circumferentially-extending grooves formed in said recess for receiving said segments in circumferentially-slidable supporting engagement, said 30 casing formed with a loading slot communicating with said recess for receiving said segments individually for movement into slidable engagement with said grooves, such that said segments may be individually inserted into said recess through said loading slot and slid along said 35 grooves to assemble said shroud ring as a complete annulus in said recess.

2. In a turbine engine of the type comprising an annular casing partially defining a working fluid duct, a row of blades mounted for rotation in said duct, and a row of 40 guide vanes in said duct for guiding a flow of working fluid therein; a stator construction for mounting said vanes in said casing, comprising, in combination; and annular shroud ring secured to an end of each of said vanes, said shroud ring divided circumferentially into a plurality of 45 arcuate segments, a pair of axially-spaced rabbets extending circumferentially about said casing and defining a recess therewith, each of said rabbets formed with a groove extending circumferentially thereabout for receiving said shroud ring in circumferentially slidable supporting engagement, one of said rabbets formed with a 50 circumferentially-extending arcuate loading slot communicating with said recess for receiving said segments individually therein, such that said segments may be individually inserted into said recess through said loading slot and slid along said grooves to assemble said shroud ring as a complete annulus in said recess.

3. A stator construction as recited in claim 2, together with an arcuate locking strip congruent with said loading slot and receivable therein by sliding in one direction, to prevent disassembly of said segments from said casing through said loading slot.

4. A stator construction as recited in claim 3, in which said locking strip and said loading slot are formed with circumferentially-spaced edges which lie in planes diverging outwardly from said casing, such that said edges cooperate to restrain said locking strip against movement relative to said loading slot in a direction transverse to said one direction.

5. In a turbine engine of the type comprising an annular casing partially defining a working fluid duct, said casing including a pair of axially abutting casing sections, a row of blades mounted for rotation in said duct, and a row of 70 guide vanes in said duct for guiding a flow of working fluid therein; a stator construction for mounting said vanes in said casing, comprising, in combination;

an annular shroud ring secured to an end of each of said vanes, said shroud ring divided circumferentially into a plurality of arcuate segments, a pair of axially-spaced rabbits extending circumferentially about a first one of said pair of casing sections and defining a recess therewith, each of said rabbits formed with a groove extending circumferentially thereabout for receiving said shroud ring in circumferentially slideable supporting engagement, one of said rabbits formed with a circumferentially-extending arcuate loading slot communicating with said recess for receiving said segments individually therein, such that said segments may be individually inserted into said recess through said loading slot and slid along said grooves to assemble said shroud ring as a complete annulus in said recess, and an arcuate locking strip congruent with said loading slot and receivable therein by sliding in one direction to prevent disassembly of said segments from said casing through said loading slot, the other of said casing sections overlying said loading slot and said locking strip to prevent movement of said locking strip relative to said loading slot in said one direction.

6. A stator construction as recited in claim 5, in which

5 movement relative to said loading slot in a direction transverse to said one direction.

10 7. A stator construction as recited in claim 5, said locking strip being formed with a lug, and one of said segments located in said recess adjacent to said loading slot being formed with a notch receiving said lug and co-operating therewith to prevent circumferential sliding of said shroud ring in said grooves subsequent to assembly of said stator construction.

said locking strip and said loading slot are formed with circumferential edges which lie in planes which diverge outwardly from said casing, such that said circumferential edges cooperate to restrain said locking strip against

5 movement relative to said loading slot in a direction transverse to said one direction.

10 7. A stator construction as recited in claim 5, said locking strip being formed with a lug, and one of said segments located in said recess adjacent to said loading slot being formed with a notch receiving said lug and co-operating therewith to prevent circumferential sliding of said shroud ring in said grooves subsequent to assembly of said stator construction.
